Attorney

UNITED STATES PATENT OFFICE.

CHARLES J. HEUSER, OF PATERSON, NEW JERSEY.

DOOR LATCH.

Application filed March 14, 1928. Serial No. 261,593.

The object of my invention is the provision of a latch, designed more particularly for use on heavy swinging doors, and one that is simple in construction and reliable in operation, and is susceptible of being quickly and easily installed with the formation of but a single opening through the thickness of one door.

With the foregoing in mind, the invention in all of its details will be fully understood from the following description and claim when the same are read in connection with the drawings, accompanying and forming part of this specification, in which:

15 Figure 1 is an elevation showing my novel latch in working position.

Figures 2 and 3 are sections on the lines 2—2 and 3—3, respectively, of Figure 1.

Similar numerals of reference designate 20 corresponding parts in all figures.

I show in Figures 1 and 2, two doors 1 and 2 of horizontal swinging type adapted when closed to rest edge to edge.

The door 1 is provided at 3 with an opening which extends through its thickness, and in the said opening are casing sections 4, of appropriate metal, shaped as shown and arranged end to end, Figures 2 and 3, and equipped with escutcheons 5, attached to 30 opposite sides of the door.

A lifting lever 6 is pivoted at 7 in one casing section 4, and is provided with a pendent handle 8.

Alongside the escutcheon 5 of one casing section 4 is arranged a beveled keeper 9 having a pendent shank 10 fixed to one side of the door 1.

Fixed to the corresponding side of the door 2 is a wear and stop plate 11, and movable vertically in opposed relation to said plate 11 is a vertically swingable latch lever 12, pivotally connected at 13 to a plate 14, fixed on one side of the door 2. The lever 12 extends above the keeper 9 and lifting lever 6, and is provided at its free end with a return arm 14 of reduced rod-like form in cross-section, the said arm 14 being joined by a bight 15, Figure 2, to the major portion of the lever 12 and being arranged to 45 rest in front of the major portion of lever 12, Figures 1, 2 and 3, and constitute a convenient handle for lifting of the lever 12 by a person at one side of the doors 1 and 2. Manifestly the lever 12 is lifted by

a person at the opposite side of the doors 1 55 and 2 through the medium of the lever 6.

In the preferred embodiment of my invention the latch lever 12 is arranged and adapted to play in a guide 16 affixed to the side of the door 2.

It will be apparent from the foregoing that when the door 2 swings to the position illustrated relative to door 1, the lever 12 will ride over and seat behind the keeper 9 and thereby securely fasten both doors in 65 closed position; also, that precedent to opening of the doors 1 and 2 the lever 12 may be lifted and disengaged from the keeper 9 either by stress applied to the hand grasp 70 14 or by stress applied to the handle 8 of lift lever 6, the latter by a person at the opposite side of the doors, with reference to the latch lever 12.

It will further be appreciated from the foregoing that my novel latch is simple, 75 strong and compact, and is susceptible of quick and easy installation, the latter being due in a considerable measure to the employment of the opposed casing sections 4 in the opening 3.

Having described my invention, what I claim and desire to secure by Letters Patent, is:

In combination a beveled keeper, means carrying the same and having an opening, a 85 lift lever mounted in the opening of said means and disposed transversely thereof, a vertically swingable latch lever pivoted at one end and engageable with the keeper and the lift lever and having a loop at its free 90 end and a reduced hand-grasp portion constituting a rearwardly extending portion of said loop and spaced in front of and opposite the keeper and lift lever, means carrying said latch lever; one of said means being movable relative to the other, a stop plate carried by and extending from one of said means to bring up against the side of the other means, and casing sections arranged end to end in the transverse opening of the first-named means and having outer escutcheons attached to said means, one of said casing sections having secured therein and carrying the said lift lever.

In testimony whereof, I affix my signature.

CHARLES J. HEUSER.
